CLAIM

I claim the ornamental design for a post element for an outdoor enclosure, as shown and described.

DESCRIPTION

FIG. 1 is a perspective view of a post element for an outdoor enclosure, showing my new design;

FIG. 2 is a front elevational view of the post element for an outdoor enclosure of FIG. 1;

FIG. 3 is a rear elevational view of the post element for an outdoor enclosure of FIG. 1;

FIG. 4 is a right side elevational view of the post element for an outdoor enclosure of FIG. 1;

FIG. 5 is a left side elevational view of the post element for an outdoor enclosure of FIG. 1;

FIG. 6 is a top plan view of the post element for an outdoor enclosure of FIG. 1; and,

FIG. 7 is a bottom plan view of the post element for an outdoor enclosure of FIG. 1.
